LOUD SPEAKER

Filed March 8, 1930

UNITED STATES PATENT OFFICE

CARL A. BERGMANN, OF BROOKLYN, NEW YORK

LOUD SPEAKER

Application filed March 8, 1930. Serial No. 434,196.

The invention relates to loud speakers for radio receiving apparatus and more particularly to that class commonly referred to as dynamic speakers.

The indicated type of speakers include in their construction an element generally termed a speaker pot which is usually of cylindrical or other predetermined form and is arranged to contain the pole core which 5 co-operates with the usual voice coil tube and the customary cone to effect sound amplification, and the conventional magnet coil which surrounds the core. In existing constructions it has been deemed essential to proper 10 and efficient operation to provide the speaker pot with a continuous and uninterrupted peripheral wall in order to secure the desired magnetic action. Because of this fact it has been necessary to make one of the end 15 walls of such pots as separate, independent units, combined with the cylindrical bodies of the pots so as to be capable of being removed in order that the magnet coil may be 20 properly inserted into place. With such an arrangement the opposed surfaces of the body and removable wall of the speaker pot must 25 fit each other very exactly and accordingly must be machined with extreme care and exactness in order to prevent interference with 30 the magnetic flow; experience has shown however that such interference is not entirely eliminated even under the most careful conditions of manufacture and assembly.

In dynamic speakers of the class in question the core is fixed upon the integral wall 35 of the pot and projects toward an opening in the removable wall in which the voice coil tube is accommodated. Actual practice has 40 developed the fact that efficient sound reproduction and amplification can be produced only if an annular slot or space of exact uniformity throughout is provided between the voice coil tube and the contiguous portion of the speaker pot. With existing constructions it has 45 been difficult, if not impossible, to provide the necessary axial registry in the drilling of the two end walls of the pot to provide the aforesaid annular slot or space of exact uniformity, with the result that defective 50 speakers are created unless the utmost preci-

sion is observed in the manufacture and assembly.

Even, if initially, the result is satisfactory relative changes which may take place in the body and the removable wall of the pot, or the means whereby the latter is connected with the body, cause disturbance of such satisfactory conditions after the speaker has been in use even for only a comparatively short space of time. Obviously the extreme precision 55 which is required to produce even a temporarily efficient loud speaker increases the cost of production and assembly materially.

The object of the invention is to provide 60 a speaker pot of the type referred to in which the above objections and others inherent in existing constructions are avoided and whereby a speaker pot of maximum efficiency throughout its life is produced at relatively 65 low cost and without the necessity for any extreme precision and highly paid skilled labor.

Other more specific objects will appear 70 from the description hereinafter and the features of novelty will be pointed out in the 75 claims.

In the accompanying drawings which illustrate an example of the invention without defining its limits Fig. 1 is a side elevation of a dynamic loud speaker embodying the novel features; Fig. 2 is a side view of a 80 speaker pot; Fig. 3 is a central sectional elevation of the speaker pot and Fig. 4 is an end view thereof.

The novel speaker pot comprises a hollow 85 metallic body of cylindrical or other predetermined form and consisting of a peripheral wall 5 and opposite end walls 6 and 7. The latter are cast in one piece, with, or otherwise made as integral parts of the peripheral wall 5 which is interrupted or provided with at least one opening 8, dimensioned to admit the customary magnet coil 9 to the interior 90 of the pot as will be more fully set forth hereinafter; the opposite end walls 6 and 7 are provided respectively with apertures 10 and 11, the aperture 10 being dimensioned 95 to receive the screw-threaded stem or other fastening device 12 of the customary pole core 13, which stem 12 is arranged to receive 100

a nut 14 whereby said pole core is securely fixed upon the end wall 6. The pole core 13 projects from said wall 6 into the aperture 11 of the end wall 7 which aperture 11 is dimensioned to form with said core 13 an annular slot 15 of uniform size throughout as shown in Figs. 3 and 4. The customary voice coil tube 16 extends into the annular slot 15 in the well known way and is combined with the conventional cone 17 in the conventional manner. The cone 17 may be supported by means of any usual or customary support which in the illustrated example comprises a frame 18 carried by arms 19 which are secured to the end wall 7 of the pot by means of screws 20.

In practice the magnet coil 9 is inserted through the opening 8 into the interior of the pot and is shifted into position until its axial opening registers with the apertures 10 and 11. The pole core 13 is then inserted through the aperture 11 and the axial opening of the coil 9 and its screwthreaded stem 12 projected through the aperture 10; when this has been accomplished the nut 14 is screwed home upon the stem 12 to firmly fix the pole core 13 and the magnet coil 9 in position in the pot. The other elements of the loud speaker are then fastened in place in any convenient and conventional sequence.

Because of the fact that the end walls and peripheral wall of the speaker pot are cast in one piece, or otherwise made as integral parts of each other, the speaker pot is entirely free from any joints or dividing lines between surfaces of separate parts which tend to develop interference with the magnetic action of the loud speaker. At the same time because of the resulting fixed relation between the end walls 6 and 7 the apertures 10 and 11 may be drilled or otherwise produced in said end walls respectively with absolute axial registry, with a minimum of effort and without the necessity for any particular skill. Because of this fact and due to the aforesaid fixed relation between the end walls 6 and 7 the pole core 13 when secured in place in the speaker pot will be perfectly centered in the aperture 11 without requiring any special adjustment or skill to bring this about, with the result that the annular slot 15 will always be of uniform and exact dimensions throughout its entirety. With the arrangement set forth it is also a comparatively simple matter to place the magnet coil 9 in proper position and to otherwise completely assemble the loud speaker.

The necessity for any special machining of contacting parts is reduced to a minimum and makes the speaker pot easy to produce by relatively unskilled labor and consequently reduces the cost of production to a minimum. By making the peripheral and end walls of the speaker pot as integral parts of each other the development of interference with

the efficient magnetic action of the speaker due to relative physical changes in independent elements is also entirely avoided. In other words, the novel construction provides a speaker pot for dynamic loud speakers which is of maximum efficiency throughout its life and is capable of being produced and assembled with a minimum of effort and expense.

It will be understood that the construction, dimensions and shape of the speaker pot will be determined by the nature and character of the co-operating parts of the loud speaker for which it is designed but will always be such as to embody the novel features of the invention.

Various changes in the specific form shown and described may be made within the scope of the claims without departing from the spirit of the invention.

I claim:

1. A speaker pot for dynamic loud speakers, comprising a hollow metallic body all parts of which are integral with each other and provided with an opening in its peripheral wall dimensioned to admit a magnet coil to the interior of said body.

2. A speaker pot for dynamic loud speakers, comprising a hollow metallic body consisting of a peripheral wall and opposite end walls cast as integral parts of said peripheral wall, the latter being provided with an opening dimensioned to admit a magnet coil to the interior of said body.

3. A speaker pot for dynamic loud speakers, comprising a hollow metallic body consisting of a peripheral wall and opposite end walls cast as integral parts of said peripheral wall, the latter being provided with an opening dimensioned to admit a magnet coil to the interior of said body, and said end walls being provided with apertures in axial registry with each other, one of said apertures being dimensioned to receive a fastening means for securing a pole core to the one end wall, and the other aperture being dimensioned to form, with said core, an annular slot of uniform size throughout.

In testimony whereof I have hereunto set my hand.

CARL A. BERGMANN.
